(57) **CLAIM**

The ornamental design for electric stroller for infants as shown and described.

DESCRIPTION

FIG. 1 is a perspective view of the electric stroller for infants according to the present invention.

FIG. 2 is a front view of the electric stroller for infants of FIG. 1.

FIG. 3 is a rear view of the electric stroller for infants of FIG. 1.

FIG. 4 is a left side view of the electric stroller for infants of FIG. 1.

FIG. 5 is a right side view of the electric stroller for infants of FIG. 1.

FIG. 6 is a top view of the electric stroller for infants of FIG. 1; and,

FIG. 7 is a bottom view of the electric stroller for infants of FIG. 1.

The broken lines in the drawings illustrate portions of the electric stroller for infants that form no part of the claimed design.

1 Claim, 7 Drawing Sheets
